UNITED STATES PATENT OFFICE.

WILLIAM WILSON, OF SELMA, ALABAMA.

HAT-STEAMING MACHINE.

Application filed January 30, 1924. Serial No. 689,410.

To all whom it may concern:

Be it known that I, WILLIAM WILSON, a citizen of the United States, and a resident of Selma, in the county of Dallas, in the State of Alabama, have invented certain new and useful Improvements in Hat-Steaming Machines, of which the following is a full, clear, and exact description, reference being had to the accompanying drawing, 10 forming part of this specification.

My invention relates to machines for steaming and blocking the crowns and brims of hats, of the kind shown in my former Patent No. 1,441,258 of January 9th, 1923, 15 and it has special relation to improvements in the steaming bell whereby the efficiency of the apparatus may be greatly enhanced.

One of the principal features of my improved device is the construction whereby 20 the water of condensation is effectively taken care of and prevented from leaking through the perforations and coming into contact with the hat, so that any hat may be steamed and blocked immediately without waiting until the outer shell has become 25 so hot as to eliminate condensation, and at the same time effecting a great saving in the steam hereto required for the preliminary heating of the bell.

Another feature of the invention consists 30 in the improved construction of inner and outer shells for strength and durability, and to permit the joining of the two parts readily and easily with steam and waterproof 35 gasketed joints, and further to provide a seamless trough for the collection and disposal of the water of condensation and to effectively provide for the drainage of the crown portion of the bell.

The above features of the improvement 40 and other features not above mentioned will be hereinafter more particularly pointed out and claimed in the specifications that follow.

In the drawing:

Figure 1 is an enlarged central vertical 45 section of the steaming bell.

Figure 2 is a side elevation of the entire 50 machine reduced in size.

Figure 3 is a perspective view partly in 55 section of the band block.

While my present improvements relate 60 particularly to the steaming bell and block, adapted for use with other standards and operating mechanism, I have shown in Figure 2 an illustration of the machine of my

prior Patent No. 1,441,258, of January 9, 1923, in which the steaming bell is mounted on an inclined standard 1, which carries the vertically adjustable table 2 sliding on guides 3 with connecting bars 4 to the foot 60 treadle 5, by the operation of which the table is raised to bring the stand 6 with the proper sized flange block 7 under the steaming bell.

The steaming bell comprises an imperforate outer metallic shell or casing 8, and a perforated inner metallic shell 9, the walls of both of which are made of substantial thickness to give strength and durability.

Each of the shells has outwardly curved 70 flanges 10, 11 and at the juncture of the flange, the outer shell is provided with an inner circumferential rib 12 which fits in an annular seat 13 in the inner shell.

A gasket 14 is provided for this joint and 75 the parts are drawn tightly together by counter-sunk screws 15 at suitable points, so as to provide a steam and water-tight joint. The lower end 18 of the flange 11 of the perforated shell is turned up and engages within a seat 16 formed in the lower edge of the flange of the outer shell and a gasket 17 is applied at this joint and the parts secured together by countersunk 80 screws 19.

This method of providing joints which 85 may be supplied with gaskets and thus may be made steam and water-tight is much preferable to any machined joint such as suggested in my former patent, and also 90 permits the shells to be readily and easily opened up for cleaning or otherwise.

In order to prevent any water of condensation leaking through the perforations 20 of the inner bell 9, I provide metal shields 95 21 which are attached by bolts 22 with spacing washers 23 to cover the perforations 20, allowing sufficient space, however, for the free circulation of steam. These shields are preferably made of suitable, non-corrosive 100 metal, as thin as compatible with strength and durability, but adapted to heat very quickly, so as to condense as little steam as possible.

The rib 12 is provided with openings in 105 which drain pipes 24 are inserted to drain any water of condensation from the crown portion of the bell into the brim portion above the shield plates, which water collects 110 in the seamless trough 25 in the turned up

portion of the inner flange whence it is carried to and removed by the drain pipe 26 at the rear.

Of course, where the bell is used with an inclined standard, only one drain pipe 24 will be necessary.

The steam is supplied to the two compartments, the one for the crown and the other for the brim through a steam supply pipe 27, which for convenience passes up through the standard and thence through properly valved branch pipes to a coil 28, in the crown portion and a coil 29 in the brim portion of the bell, both of the coils being 15 plugged at their outer ends and provided with perforations along their respective lengths for the delivery of the steam.

In order to protect the sweat band of the hat under treatment, so that it shall not 20 be necessary to remove the sweat band, I provide a band block comprising a solid plate 30, with a circular flange 31 to embrace the sweat band, and formed with a projecting lip 32. This lip may be a 25 straight lip, but I prefer to provide a curved lip, as it more effectively protects the head of the sweat band. A handle 33 is secured across the flanged portion for easy manipulation.

It will be understood, of course, that for 30 the steaming bell above described, flange blocks for the brims and sweat band blocks for the inside of the hat, will be furnished of the standard sizes of hats, so that the 35 steaming bell can be used for all of the ordinary sizes of hats.

The manipulation of the machine will be 40 obvious and is the same as in my heretofore mentioned patent, and need not be again described, except possibly to point out that the protection of the perforations of the inner casing against the leaking of condensed steam, permits the re-blocking and reforming of the hat at a moment's notice, without 45 the delay heretofore necessary in first

heating up the bell to avoid condensation which condensation was not even then entirely avoided.

Having thus described my invention, what I claim as new and desire to secure by Letters Patent, is:—

1. A steaming bell for hats comprising an imperforate outer shell and a perforated inner shell, with means to hold the shells in spaced relation and to form a steam tight compartment, a perforated steam pipe for said compartment, with metallic shields of thin material interposed between the perforated coil and the perforations of the inner shell to prevent leakage of condensed 55 water therethrough.

2. A steaming bell for hats comprising an imperforate outer shell and a perforated inner shell, with a rib to hold the shells in spaced relation and to divide the inner 65 space into two compartments with a coil of steam pipe in each compartment, and metallic shields interposed between the perforated coils and the perforations of the inner shell to prevent leakage of condensed 70 water therethrough, and drainage communication between the compartments to carry off the drainage water therefrom.

3. A steaming bell for hats comprising an imperforate outer shell and a perforated inner shell with a rib to hold the shells in spaced relation and to divide the inner space 75 into two compartments, with a coil of steam pipe in each compartment, and metallic shields interposed between the perforated 80 coils and the perforations of the inner shell to prevent leakage of condensed water therethrough, and drainage communication between the compartments to carry off the drainage water therefrom, with a trough in 85 the bottom of the lower compartment to receive the drainage water and deliver it from the bell.

WILLIAM WILSON.
